TABLE GAME

Louis Charles Gross, Chicago, Ill.

Application March 10, 1932. Serial No. 598,070

1 Claim. (Cl. 273—125)

This invention relates to the broad class of games and amusement devices and has more specific reference to a table game of the type utilizing one or more projectible balls co-operable with suitably numbered pockets into and through which the projected ball rolls for conveniently computing the individual scores of competitive participants.

The present invention is similar in respect to game tables of the aforesaid type so far as the general principle of play is concerned, but structurally distinguished from known marketed and prior art devices, whereby to provide an appreciable and novel contribution to the art and the trade.

One structural improvement is the composite or laminated tabletop whose bottom is constructed to include an upper ply of wall board or equivalent shock and noise absorbing material. Another feature of the invention is dependent on the use of wooden projectiles or balls especially selected for co-operation with the noise absorbing table top said ball having the additional function of providing the requisite degree of resilient properties producing indeterminable bouncing and coming into contact with the complementary obstructions around the pocket in order to effect the element of chance of securing a high score.

Another feature of the invention is based on the use of a detachable suitably shaped ball trapping and return tray constructed to facilitate expeditious retrieving of the balls for successive usage.

Other features and advantages will become more readily apparent from the following description and drawings.

In the drawings:

Figure 1 is a top plan view.

Figure 2 is a longitudinal section, taken on the line 2—2 of Figure 1.

Figure 3 is a transverse section taken on the plane of the line 3—3 of Figure 1.

Figure 4 is an end elevational view of the playing end of the table.

Figure 5 is an enlarged detail view on the line 5—5 of Figure 6.

Figure 6 is a bottom plan view of Figure 1.

Figure 7 is a perspective view of the ball trapping and return tray.

Figures 8 and 9 are detail views of the que and ball respectively.

Figure 10 is a perspective detail view of one of the hinged legs.

The table top is generally designated by the numeral 11 and occupies a rearwardly and down-

wardly inclined position when in use as shown for example in Figure 2. It has a two ply laminated bottom, the lower ply 12 being of wood and the topping ply 13 of wallboard or equivalent shock and noise absorbing properties. The numeral 14 designates the marginal ball confining rim and 15 indicates the front corner block having curved abutment faces against which the wooden ball 16 is adapted to be shot by the que stick 17.

The ball is placed on a suitable starting plate 18 at the shooting end of the narrow alley or ballway 19. Incidentally this is defined by the presence of a strip 20. The numeral 21 merely designates what may be distinguished as a dead-line mark. The ball must travel beyond this mark under the action of the shot before it is counted as being in action in the field of play.

The boards 12 and 13 are formed at suitably spaced points with holes 22 serving as passages through which the wooden ball is allowed to drop. These are surrounded by obstruction pins 23 appropriately arranged. Moreover the pockets are appropriately numbered in desired progressive order. Underneath the primary pocket is a bell 22a indicative of the highest score of points to be made on the table.

The numerals 24 designate transverse longitudinally disposed cleats to which the supporting legs 25 are hingedly connected as at 26. The legs 25 are connected together in pairs by connecting bars 27. Each leg is formed at its top with a retaining clip or plate 28 having a notch 29 at its upper end for reception of the retaining screw 30 which may be removed when it is desired to fold the leg frames against the bottom of the table for storage and transportation purposes.

The ball or balls dropping through the holes 22 are trapped in the receptacle or tray 31. This is in the form of a longitudinally tapered box-like tray shallow at the upper end and much deeper at the lower end. At the last named end and towards one corner the bottom 32 of the tray slants towards a discharge hole 33 found in one side wall and attached to this part of the bottom and projecting out beyond and in alignment with the hole 33 is the ball return and receiving pan or cup 34. The tray 31 and its cup 34 constitutes a single unit releasably clamped against the bottom of the table by way of hanger hooks 35 100 and 36.

By turning the bill of the hook out beyond the edge of the tray it is obvious that it may be bodily detached from the table.

It is to be observed that the passages or holes 110

are so located as to permit the ball trapping and return tray to be supported directly therebeneath and as seen in Fig. 6 one of the transverse cleats constitutes a stop to aid in holding the ball return end of the tray in proper rigid position.

5 In practice, the ball is shot out from the channel or alley 19 against the block 15 and is allowed to roll or run across the surface of the table and to drop into any one of the holes as is customary 10 in games of this type. If the ball does not pass beyond the dead mark 21 it is shot over. The rules and regulations will be governed by the discretion of the players. The balls drop into the tray and are returned there from into the cup 34 15 where they are retrieved for re-use.

15 It is thought that the description taken in connection with the drawings will enable a clear 20 understanding of the invention to be had. Therefore, a more lengthy description is thought unnecessary.

While the preferred embodiment of the invention has been shown and described, it is to be understood that minor changes coming within the field of invention claimed may be resorted to if desired.

80 I claim:

In a structure of the class described, a game table, said game table having numbered openings forming ball passages, a bell disposed beneath one of said openings and adapted to be impacted by the ball for emitting a signal, a tapered ball trapping and return tray having a discharge opening at one end and a lined ball retrieving cup associated with said opening and turnable hanger hooks attached to the underside of the table for suspending the tray removably in position beneath the ball passages.
